COLLAPSIBLE OR FOLDING HIGH CHAIR
WITH A NOVEL SEAT ARRANGEMENT FOR
LOCKINGStanley Alfred Wohler, North Wales, and Walter
Bowden Pearce, Ambler, Pa.; said Wohler as-
signor to said Pearce

Application June 2, 1949, Serial No. 96,664

3 Claims. (Cl. 155—126)

1

The invention described herein, relates to high chairs which may be folded or collapsed when not in use, to permit storage in less space than heretofore required for similar devices and which can be transported with ease due to its light weight and folding qualities.

It is also the object of this invention to provide one simple means of opening or closing the chair, through a new and novel arrangement of the seat, with a positive means of locking in either the open or closed position without the use of any other hooks, catches or fasteners so as to insure the safety of the child, simplicity of operation and compactness of the chair when not in use.

Another purpose of the invention is to provide a means for having the legs so formed as to give the chair a firmness and sturdiness greatly minimizing the possibility of its being tipped over by the child while seated in the chair.

A further purpose of this invention is to provide a pivoted tray with a locking strap which not only serves to hold the tray securely in position but also prevents an enthusiastic child from sliding underneath, causing injury to the child and anxiety to the parent or guardian.

Another object of the invention is to provide joints of all members or parts, by such means as to assure greatest protection against breakage or structural failure at these points resulting in a weakened and thereby dangerous chair.

Other advantages and novel arrangements of the parts, with the construction and quality of said parts, will be apparent from the following description of the invention and accompanying drawings and specifications, of which these said drawings are a part.

Figure 1 is a side view of a high chair ready for use.

Figure 2 is a front view of a high chair ready for use.

Figure 3 is a cut-away view of a high chair in its folded or collapsed position.

Figure 4 is an enlarged partial detailed section of the seat jointure and latch arrangement.

In reference to the attached drawings, characters which are alike refer to corresponding parts.

The high chair shown in Figures 1 to 4 inclusive, preferably constructed of all metal components, includes a seat 12 supported by a pair of front legs 5 and a pair of rear legs 6, which are

5 pivoted at their upper ends at a point 19 below the upper ends of the front legs 5, and extended to the rear to provide a support for the back rest uprights 7, and the entire chair. A paneled 10 back rest 11, composed of two back uprights 7, pivoted at their lower ends at a point 20 below the upper ends of the rear legs 6 and extending upward to a point 21 above the tray arms 9. The back uprights 7, are connected adjacent to each 15 other at a point above the lower ends and slightly below the center of said back uprights 7, by a latch bar 15, which also serves as a support for the rear of the seat 12, and a cross brace 14, at the upper ends of the back uprights 7, which also serves as a handle for carrying while folded.

The side braces 8, as shown in Figure 1, are pivoted at their upper ends at a point 22 to the upper ends of the front legs 5. These side braces 8 extend down and to the rear and are pivoted 20 at their lower ends to the back uprights 7, at a point 23 above the lower ends of said back uprights 7, and slightly below the latch bar 15.

The front legs 5 are connected adjacent to each other by a cross brace 16, located at a point midway between the upper and lower ends of said front legs 5, and by another cross brace 17 at a point above the lower ends of the front legs 5.

The rear legs 6, are connected adjacent to each other by a cross brace 18, located at a point above the lower ends of said rear legs 6.

The tray 10, is attached to tray arms 9, as shown in Figure 1, at a point from the outer ends of said tray arms 9, and is so placed as to give ample room for clearance above the child's head when said tray 10, is swung into or out of position.

The tray arms 9, are pivoted at a point 21 below the upper ends of the back uprights 7, and at the upper ends of said tray arms 9, and so placed as to provide ample clearance above the head of the child when the tray 10, is moved into position. The tray 10, rests upon the upper ends of the front legs 5, and side braces 8, and is held in position by a safety strap 13, secured at one end to the front of the seat 12, and provided with a suitable locking means to be fastened to the tray 10, at its outer or front edge.

A seat 12, as shown in Figure 4, is pivoted at front side portions and is connected to the chair at the juncture 19 of the front legs 5, and the rear legs 6, with the sides of said seat 12 being so formed with a cam-like contour as to provide

a sliding and self-locking action when the chair is in a collapsed or folded position as in Figure 3, or extended for use as in Figure 1. Said sides of seat 12, have notches at rear portions, said notches extending upward to approximately midway of the side face of the seat 12, as in Figure 4.

When the chair is in the open or extended position as in Figures 1 and 2, the notches in the side faces of seat 12, fit over the latch bar 15, as shown in Figure 4, thereby locking the chair in position and further secured by the weight of the child and causing the back rest 11 to slant to the rear, thus forming a comfortable position for the child. The tray 10 is brought forward over the back rest 11 to rest upon the upper ends of the front legs 5 and side braces 8 and is then in the proper location for use.

When folding or collapsing the chair for storage or transportation, as shown in Figure 3, the tray 10 is swung over the back rest 11, and then the rear portion of the seat 12, is pulled upward thereby releasing the seat 12 from the latch bar 15 in the back rest 11, permitting the front legs 5, and rear legs 6, to be swung toward each other on the pivots and so collapsing the chair.

When the chair is being folded or collapsed, the novel arrangement of the sides of the seat 12, as in Figure 4, permits the seat 12 to slide to the rear and over the latch bar 15, in the back rest 11, moving into a vertical position as in Figure 3, thereby holding the front legs 5 tightly against the rear legs 6 and the back rest 11, preventing the chair from being extended by any means other than further movement upward of the rear of the seat 12.

The safety strap 13 is then connected to the tray 10 as shown in Figure 3, positively locking the entire structure of the chair for transportation.

When the chair is extended to the open position as in Figures 1 and 2, the seat 12 is pulled forward until the notches in the sides of the seat 12 drop over the latch bar 15 in the back rest 11, thereby securing the entire chair in the open position and ready for use. Movement of the seat 12 in this manner causes the front legs 5, the rear legs 6 and the back rest 11, to be extended to the proper position for use. The tray 10 is then brought forward over the back rest 11 into position and secured by the safety strap 13 fastened at its lower end to the front of the seat 12.

The legs 5 and 6 as shown in Figure 2, are so constructed or formed as to have their lower portion extended outward for a suitable distance thereby providing additional stability and sturdiness to the chair while in use.

From the description of the invention herein described it will be seen that provision has been made for a collapsible or folding high chair which, by means of a new and novel seat arrangement and other component parts of the chair, may be held in either an open or closed position without any other attached locking devices, levers or catches and using only said seat and component parts of the structure to provide a more satisfactory and easily operated high chair.

We realize that changes may be made and construction details varied without departing from the desires of the inventors or the range of the invention herein described and we therefore present the following claims as our invention.

We claim:

1. A folding chair comprising a pair of front legs, a pair of rear legs pivotally connected at

their upper ends to the front legs substantially below the upper ends of the front legs, a back rest having members pivotally connected at their lower ends to the rear legs in the region of the midportions of the rear legs, a pair of side braces pivotally connected to the upper ends of the front legs and extending downwardly and rearwardly to pivotal connections with the back rest members substantially above the lower ends of the back rest members, the portions of the front legs, the rear legs, the back rest members and the side braces within the pivotal connections being in parallelogram relation, and a seat pivotally connected to the front legs and supported by the back rest members.

2. A folding chair comprising a pair of front legs, a pair of rear legs pivotally connected at their upper ends to the front legs substantially below the upper ends of the front legs, a back rest having members pivotally connected at their lower ends to the rear legs in the region of the midportions of the rear legs, a pair of side braces pivotally connected to the upper ends of the front legs and extending downwardly and rearwardly to pivotal connections with the back rest members substantially above the lower ends of the back rest members, a seat, means pivotally connecting the forward portion of the seat to the front legs and means attached to the back rest members for supporting the rearward portion of the seat, the portions of the front legs, the rear legs, the back rest members and the side braces within the pivotal connections being in parallelogram relation, the seat having side portions formed to provide clearance with the means for supporting the rearward portion of the seat when the chair is in folded position with the front legs and back rest members adjacent to each other and the seat hanging vertically downwardly back of the means for supporting the rearward portion of the seat, the seat hanging from the means pivotally connecting the forward portion of the seat to the front legs.

3. A folding chair comprising a pair of front legs, a pair of rear legs pivotally connected at their upper ends to the front legs substantially below the upper ends of the front legs, a back rest having members pivotally connected at their lower ends to the rear legs in the region of the midportion of the rear legs, a pair of side braces pivotally connected to the upper ends of the front legs and extending downwardly and rearwardly to pivotal connections with the back rest members substantially above the lower ends of the back rest members, a seat, means pivotally connecting the forward portion of the seat to the front legs, means attached to the back rest members for supporting the rearward portion of the seat, the portions of the front legs, the rear legs, the back rest members and the side braces within the pivotal connections being in parallelogram relation, the seat having side portions formed to provide clearance with the means for supporting the rearward portion of the seat when the chair is in folded position with the front legs and back rest members adjacent to each other and the seat hanging vertically downwardly back of the means for supporting the rearward portion of the seat, the seat hanging from the means pivotally connecting the forward portion of the seat to the front legs, and arm members pivotally connected at their upper ends to the back rest members hanging downwardly and forwardly therefrom and supporting a tray at their forward

ends, the forward portions of the arm members being supported by the front legs, the arm members being rotated about their pivotal connections with the back rest members and hanging downwardly therefrom back of the hanging seat when the chair is in folded position.
